UNITED STATES PATENT OFFICE.

HORATIO STARK WILKINSON, OF JEFFERSON PARISH, ASSIGNOR OF ONE-HALF TO PHILLIP KEY THOMPSON, OF NEW ORLEANS, LOUISIANA.

HARVESTER.

SPECIFICATION forming part of Letters Patent No. 337,542, dated March 9, 1886.

Application filed January 26, 1885. Serial No. 154,074. (No model.)

To all whom it may concern:

Be it known that I, HORATIO STARK WILKINSON, a citizen of the United States, residing in the parish of Jefferson, and State of Louisiana, have invented a new and useful Swathing Attachment for Harvesting-Machines, of which the following is a specification.

My invention relates to that class of harvesting-machines wherein the cut grain is transported from the receiving-platform upwardly by means of an inclined endless apron leading from said platform, and is afterward deposited upon the stubble to dry. Machines of this character are intended to be used where the grain at the time of harvesting is too moist or wet to be bound at once into sheaves without suffering subsequent deterioration, and where, consequently, it is impracticable to employ the ordinary self-binding harvester.

My invention comprehends means, substantially as hereinafter described, and particularly pointed out in the claims, for receiving the cut grain from the summit of the endless apron and dropping it in an even continuous swath upon the stubble, at right angles to the path of movement of the machine.

Referring to the drawings accompanying this specification and illustrative of my invention, Figure 1 represents in plan a detail view of the receiving-apron constituting a portion of my improved swathing attachment, said apron being shown as detached from the machine and spread out in semicircular form.

Fig. 2 represents, in plan, a view of the complete attachment secured to the harvesting-machine. Figs. 3 and 4 represent detail views of the terminal rollers actuating the apron of the swathing attachment. Figs. 5 and 6 represent, respectively, rear and side elevations of the attachment in its relationship to the main machine. Fig. 7 and 8 represent in detail enlarged views of the means for imparting motion to the rollers of the receiving-apron of the attachment; and Fig. 9 represents in perspective a view of a complete harvester and the attachment combined in the relationship contemplated in my invention.

Similar letters of reference indicate similar parts throughout the several views.

M indicates a harvester of the ordinary type, provided with the delivery-apron I, operated as usual from the driving-gear of the machine.

Upon the rear frame-work of the machine are mounted a series of sprocket-wheels, as shown, operated by a sprocket-chain, A', which receives motion from the driving-gear. One of these wheels, A, is mounted upon the upright L, being secured to a shaft, B', passing through said upright, and having its outer bearing in one extremity of a quadrant, F. A collar, C, is secured to the upright L, and is perforated, as shown at D", to form the inner bearing of a shaft, D', extending outwardly at right angles to the shaft B', and having its outer bearing in the other extremity of the quadrant F. Upon these shafts are mounted conical rollers B'D, and over and under these rollers is stretched the apron G, formed of canvas, with radial slats attached thereto at equal distances from each other, the ends of the apron being joined, so as to form an endless quadrangular traveling bed. The apron is cut away at its center R, as shown, and the inner ends of the slats abut against each other along the edges of the said opening; protecting the fabric from wear at that point.

Above and below the collar C are located the idle-wheels E E, which are interposed between the apron G and the upright L, for the purpose of diminishing friction between the two.

At the delivery end of the apron G are located the spring-fingers I', which guide the grain to the stubble. The quadrant F is sustained by the under braces, K K, and top braces, H H, connected to the main framework.

The operation of my invention is clearly apparent. The roller B, operated from the driving-gear of the machine through the medium of the sprocket-chain A' and wheel A, operates in its turn the traveling apron G, which, receiving the grain from the delivery end of the apron I, turns it at right angles to its position when mounting said apron I, and drops

it upon the stubble from the guide-fingers I'. The latter serve to retain the grain in position during its descent to the ground and deliver it in an even continuous swath.

5 My invention is especially adapted for use in harvesting rice, but may be employed generally wherever it is desirable to dry the cut grain before binding it.

Having thus described my invention, what 10 I claim, and desire to secure by Letters Patent, is—

1. In a harvester, the combination, with the elevator-apron I, of the quadrangular apron G, located at the top of the elevator, and 15 guide-fingers I', depending toward the rear from the quadrangular apron, whereby the cut grain is elevated, turned at right angles

to the path of movement of the machine, and dropped in an even continuous swath upon the stubble at one side of and at right angles 20 to said path, substantially as shown and described.

2. In a harvester, the apron G, cut away at its center, as shown, and provided with a series of slats radiating from said opening and 25 abutting at their inner ends, in combination with the upright L, and friction-rollers intermediate between said upright and slat ends, substantially as shown and described.

HORATIO STARK WILKINSON.
